Patented Sept. 7, 1920.

Percy P. Sanford Inventor

By His Attorney

Edmund G. Gordon

UNITED STATES PATENT OFFICE.

PERCY PHELPS SANFORD, OF WOODRIDGE, NEW YORK.

FOUNTAIN-PEN.

1,351,873.

Specification of Letters Patent.

Patented Sept. 7, 1920.

Application filed July 3, 1919. Serial No. 308,581.

To all whom it may concern:

Be it known that I, PERCY PHELPS SANFORD, a citizen of the United States, residing at Woodridge, in the county of Sullivan, State of New York, have invented certain new and useful Improvements in Fountain-Pens; and I do hereby declare the following to be a full, clear, and exact description of the invention, such as will enable others skilled in the art to which it appertains to make and use the same.

This invention relates to fountain pens and more particularly to an improved ink-feeding device for fountain pens.

The most important feature for the successful operation of any fountain pen is the uniformity and accuracy of the ink-feeding device. To maintain a uniform ink flow regardless of the quantity of ink in the barrel, the air pressure of the barrel should be substantially uniform. As the ink is supplied from the barrel to the pen, it is necessary to replace the ink removed with an equal volume of air to prevent the creation of a vacuum or an excess pressure in the barrel. A large number of different forms of ink-feeding devices have been made for maintaining a uniform flow of ink, and although many of these devices have a well regulated flow of ink when the barrel is nearly full of ink, they have a very full flow of ink when the barrel is becoming empty.

The primary object of the present invention is to provide an ink-feeding device for a fountain pen which will give a uniform and regulated flow of ink. The fountain pen illustrated in the drawings is arranged to provide an ink-feeding device which may be easily adapted for use with any of the various kinds of steel pens so as to allow a new pen to be frequently substituted. Practically all of the fountain pens on the market use a gold pen point which is permanently fixed in the pen and the ink-feeding devices are specially molded to suit the particular pen point used. To obtain the various kinds of pen points for different kinds of writing, such as fine, coarse and medium, it is necessary to have a separate fountain pen for each kind of pen point. Also, the permanent gold pen points have not been extensively used by accountants because the accountant prefers to use a new steel pen every

day to secure a rapid and uniform style of writing.

Accordingly, another object of the invention is to provide a feeding device for a fountain pen which may be easily and effectively adapted for use with any of the different kinds of steel pen points.

A further object of the invention is to provide an ink-feeding device for a fountain pen which will effectively prevent ink from hardening in the feed and air passages to clog the same.

With these and other objects in view, the invention consists in the improved fountain pen and ink-feeding device hereinafter described and claimed.

The various features of the invention are illustrated in the accompanying drawings, in which,

Figure 1 is a view in longitudinal section illustrating fountain pen embodying the preferred form of the invention;

Fig. 2 is a perspective view of the improved ink-feeding device;

Fig. 3 is an enlarged end view of the fountain pen with sections taken on the line 3—3 of Fig. 1; and

Fig. 4 is an enlarged cross-sectional view of the fountain pen taken on the line 4—4 of Fig. 1.

The fountain pen shown in the drawings consists of an ink barrel 10, a feed holder 12 threaded into one end of the barrel, a writing pen 14 mounted in a slot 16 in the holder 12, a feed tube 18 adjustably mounted in the holder 12, and a feed strip 20 which passes through the feed tube 18 with its outer end making a point contact with the pen 14 and its inner end extending toward the rear of the barrel 10.

The barrel 10 is preferably made of a rubber composition or it may be made of any plastic composition or metal which will not be corroded by the acid constituents used in making the ink. The most convenient form of barrel is a hollow cylinder having a closed end 22 and an open threaded end 24 arranged to receive the holder 12.

The feed holder 12 is preferably made of the same type of material as the barrel and has a threaded shank 26 arranged to coöperate with the threads 24 formed in the open end of the barrel. The slot 16 in the holder

12 has such a thickness that practically any of the various types of writing pens will be held therein by friction.

The feed tube 18 consists of a cylindrical tube formed of non-corrosive material which is slidably mounted in a bore 28 (Fig. 4) formed through the center of the holder 12. The outer end of the feed tube is turned upwardly (Fig. 1) toward the pen 14. The 5 face of the outer end of the tube 18 is substantially parallel with the longitudinal axis of the pen 14. This face, however, does not contact with the pen but is separated from the pen only a sufficient distance to permit 10 the outer end of the feed strip 20 to be adjusted for use with different kinds of pen points and to permit air to freely enter the end of the tube. The distance between the 15 face of the outer end of the feed tube and the under face of the pen is made as small as practicable so that the ink will remain 20 in the tube substantially throughout its travel to the pen. In this way, the ink is protected from evaporation and oxidation 25 and will not harden to clog the ink-feeding passage. The feed tube preferably has such a length that it may be adjusted longitudinally in the bore 28 to be adapted for use with any of the different lengths of pen 30 points and still have the inner end of the tube extending entirely through the holder 12.

The construction and arrangement of the feed strip 20 constitute an important feature 35 of the invention. The strip 20 is mounted in a pair of oppositely disposed grooves 30 (Fig. 4) formed on the inner surface of the feed tube. By this construction, the strip forms two separate and dis- 40 tinct passages through the tube, the upper passage 32 through the tube being adapted for conducting ink to the pen and the lower passage 34 being arranged to conduct air back into the barrel. Most inks contain acid 45 or acid reacting materials and the strip is preferably made of a metal which will not be affected by the constituents used in making inks. Otherwise the reaction products of the ink and metal would soon clog the 50 ink passage 32. The metals known in the trade as "nicrom" and "atarite" have been found to be suitable for this purpose. The invention, however, is not limited to the use of these metals since other non-corrosive 55 metals have been used. Although it is preferred to use grooves 30 in the sides of the feed tube 18, it is not necessary to use these grooves because with a strip 20 having a uniform 60 diameter, the joint made between the strip and the tube is sufficiently tight to form two separate and distinct passages.

To assist in obtaining a free flow of both 65 the ink and the air through the feed tube 18, the feed strip 20 is preferably polished.

The smooth surface of the metal is particularly helpful in leading air back into the barrel under a very slight vacuum suction. The feed strip 20 is shown as extending to approximately the closed end of the barrel 70 10 so that it will assist in conducting air up to the end of the barrel when it is full of ink. It is not necessary, however, to have the strip extend such a long distance 75 from the inner end of the tube 18 because once the air is past the end of the feed tube, it will readily work its way to the end of the barrel.

The feed device described above acts so efficiently to carry air into the ink barrel 80 that some kinds of ink flow out to the pen point too freely. To regulate the ink flow, a plug 36 is adjustably mounted in the passage 34 at the inner end of the feed tube 18. By adjusting the plug into and out of the 85 passage 34, the resistance to flow of the air through the passage may be varied to obtain any desired ink flow. The plug 36 further serves to maintain the feed strip 20 in any desired position if a feed tube is used 90 which is not provided with grooves 30.

The feed strip 20 also serves to deliver ink to the pen 14 since the feed tube does not touch the pen. In adapting the feed device for pens of different shapes, the outer 95 end of the feed strip is bent to make a point or line contact with the pen. To make the proper contact with the pen, the feed strip should not be a resilient or spring metal because such a metal tends to spread the pen 100 points and interferes with the free operation of the pen. For this reason, the strip 20 should be made of a non-resilient metal which is flexible or pliable and may be easily bent to touch the pen without placing a 105 pressure thereon. A short flange 38 (Figs. 1 and 2) is formed on the outer end of the feed strip which is arranged to directly contact with the pen. The flange 38 acts to change the direction of flow of the ink at 110 the point where the ink is delivered to the pen and prevents ink from dropping off the end of the feed strip.

Although the improved fountain pen described above is well adapted for use with 115 steel pens, it is apparent that it is equally well adapted for use with a permanent gold pen. The term "steel pen" as used in the specification and claims is intended to mean any of the various types of pen points which 120 are used with the ordinary holder when ink is dipped from a well. These pens may be made of steel or any of the various other approved kinds of metals.

The preferred form of the invention having been thus described, what is claimed as new is:

1. A fountain pen having, in combination, a tubular reservoir, a feed holder secured in one end of said reservoir, a pen secured 130

in said holder, a hollow feed tube mounted in said holder having a lateral opening in its end adjacent said pen, and a feed strip passing through said tube and arranged to make a point contact with said pen in the area opposite said lateral opening, said strip forming two distinct passages through said tube.

2. A fountain pen having, in combination, a tubular reservoir, a feed holder secured in one end of said reservoir, a pen mounted in said holder, a feed tube extending through said holder with its outer end presenting a lateral opening to said pen and mounted in close proximity to but spaced from said pen, and a feed strip extending through said tube with one end making a point contact with said pen within the area opposite said opening, said strip forming two separate and distinct passages through said tube.

3. A fountain pen having, in combination, a tubular reservoir, a feed tube mounted in one end of said reservoir, a pen mounted in the end of said reservoir adjacent said tube and a substantial distance into said reservoir, a feed strip passing through said tube and forming two separate and distinct passages throughout the length of said tube, said strip making a point contact with said pen.

4. A fountain pen having, in combination, a tubular reservoir, a feed tube mounted in one end of said reservoir, a pen mounted in the end of said reservoir adjacent said tube, and a feed strip passing through said tube with its outer end making a point contact with said pen and its inner end extending close to the rear of said reservoir and making contact with a wall thereof, said strip forming two separate passages through said tube.

5. A fountain pen having, in combination, a tubular reservoir, a feed tube mounted in one end of said reservoir, a pen mounted in the end of said reservoir adja-

cent said tube, a feed strip passing through said tube with its outer end making a point contact with said pen, said strip forming two separate passages which are open throughout the length of said tube, and a plug mounted in one of said passages arranged to partially close the same.

6. A fountain pen having, in combination, a tubular reservoir, a feed tube mounted in one end of said reservoir, a pen mounted in the end of said reservoir, adjacent said tube, a feed strip passing through said tube with its outer end making a point contact with said pen, said strip forming two separate upper and lower passages through said tube, and a plug mounted in the lower passage arranged to partially close the same, said plug being adjustable to vary the resistance of the flow of air through said passage.

7. A fountain pen having, in combination, a tubular reservoir, a feed tube mounted in one end of said reservoir, a pen mounted in the end of said reservoir adjacent said tube, oppositely disposed grooves throughout the length of said tube, and a feed strip passing through said tube and mounted in said grooves, said feed strip forming two separate and distinct passages through said tube, the outer end of said strip making a point contact with said pen.

8. A fountain pen having, in combination, a tubular reservoir, a feed holder secured in one end of said reservoir, a pen mounted in said holder, a feed tube extending through said holder with its outer end mounted in close proximity to but spaced from said pen, a feed strip composed of a non-corrosive, flexible, non-resilient metal extending through said tube and forming two separate and distinct passages therethrough, and a flange formed on the outer end of said strip arranged to make a point contact with said pen.

In testimony whereof I affix my signature.
PERCY PHELPS SANFORD.
